UNITED STATES PATENT OFFICE.

THOMAS H. McGOWAN, SR., OF JEWETT CITY, CONNECTICUT, ASSIGNOR TO DRAPER CORPORATION, OF HOPEDALE, MASSACHUSETTS, A CORPORATION OF MAINE.

FEELER MECHANISM.

Application filed March 15, 1927. Serial No. 175,552.

This invention relates to feeler mechanisms for looms, through the agency of which the operative condition of the loom is changed when the filling becomes substantially exhausted.

It is now the ordinary practice to equip automatic looms with feeler mechanisms which will call for a replenishment of filling prior to complete exhaustion of filling in the shuttle. Looms of this character are generally known as "feeler looms", and one of the problems that attend such looms is the conservation of waste which remains upon the filling carrier or bobbin when replenishment is effected.

It has been proposed heretofore to use certain preliminary windings or a "bunch" in an attempt to predetermine the amount of waste that will remain upon the ejected carrier or bobbin, and such bunch is usually (although not always) placed adjacent the head of the filling carrier or bobbin, and beyond the bunch the main filling winds give to the mass of filling a conical form.

The present invention has for one of its objects the provision of a feeler mechanism which shall act upon the conical winds of filling adjacent the bunch, and will be held from side slipping towards the head of the filling carrier by engagement of the teeth of the feeler with the conical winds until the latter have been withdrawn from the filling carrier or bobbin, and thereupon permit movement of the feeler longitudinally of the shuttle towards the head of the bobbin or bunch, preferably by the forward pressure of the filling carrier upon the feeler, the result being that when filling replenishment is called, the bunch will form a predetermined amount of waste.

Another important feature of the present invention consists in providing the feeler with a series of alined teeth substantially parallel to the element of the conical winds, with which it cooperates, so that the feeler may act upon the filling at a point adjacent the head of the bobbin and yet tipward of the bunch. Where the feeler is displaced by the forward pressure upon the occurrence of substantial exhaustion of filling, the teeth are ordinarily permitted to slide along the filling carrier or bobbin and frequently may cause injury thereto, and a further fea-

ture of the present invention therefore consists in providing the feeler with a projection adjacent the trailing end of the alined feeler teeth, with the result that when the feeler is initially displaced by the forward pressure against the surface of the filling carrier, the projection on the feeler will be brought into action and remove the teeth from engagement with the filling carrier and push them forwardly without engagement with the bunch adjacent the head of the bobbin or filling carrier.

The various features of the present invention will best be made clear from the following description and the accompanying drawings of one good form thereof.

In the drawings:

Fig. 1 is a perspective view of a loom at the feeler side provided with the present invention;

Fig. 2 is a plan view showing more particularly the operation of the feeler and its engagement with the filling when a working supply is present in the shuttle on detecting beats;

Fig. 3 is a similar view to that of Fig. 2 with some of the parts broken away, showing the action of the feeler when the filling is substantially exhausted on a detecting beat; and

Fig. 4 is a sectional side elevation on line 4-4 of Fig. 3.

In the present instance of the invention the feeler mechanism is associated with means for effecting replenishment of filling, but since the details of the replenishing mechanism form no part of the present invention they are not herein shown and described and may be of any usual character.

The loom frame 1 may be of usual construction and at the front thereof is the upstanding arm 2 secured to the usual transverse or change shaft common in feeler looms, and pivotally connected to the arm 2 at 3 is the rearwardly extending arm 4, the rear end portion 5 of which is adapted at times to be engaged by an operating member, shown in the present instance of the invention as the part 6, carried by the weft hammer or cam follower 7.

Pivotedly mounted at 8 on the loom frame or shipper stand is the transmitter 9 having a pin 10 underlying the arm 4. Extending

from the pivotal support 8 the transmitter has the arm 11 to which is adjustably secured at 12 the cam member 13 having the incline 14 over which extends the swinging arm 15 which may be conveniently mounted for swinging movement upon a stud 16 mounted on the shipper stand. A spring 17 normally holds the arm 15 in position, as indicated in Fig. 1. The mechanism thus far described is of usual construction and may be of any desired character.

Adjustably supported on the shipper stand or a bracket secured thereto is the feeler stand 18 in which is mounted the feeler carrier 19 normally under the influence of a spring 20 tending to move the feeler carrier rearwardly and limited in this tendency by the usual stop 21.

The feeler carrier 19 has mounted thereon the actuator 22 which in the present instance of the invention consists of an arm pivotally supported at 23 on the feeler carrier and provided with an adjustable bunter 24, the arm 22 being normally under the influence of means tending to maintain the arm 22 in its upper position, and such means as indicated in Fig. 4 consists of a spring actuated plunger or pin 25, the construction being such that should the bunter 24 be engaged by a surface on the lay as will presently be described, it will be turned upon its pivotal mounting 23 to place the end 26 of the actuator 22 in position to engage the arm 15 of the transmitting mechanism and effect replenishment of filling.

The lay 27 is provided with the usual shuttle box 28 at the feeler side of the loom, and the front wall of the shuttle box has an opening 29 which registers with a corresponding opening 30 in the wall of the shuttle when the latter is properly boxed.

The shuttle 31 carries the usual bobbin holding jaws 32 for engagement with the usual rings 33 on the head of the filling carrier or bobbin 34.

In accordance with the present invention, the filling carrier or bobbin 34 has a bunch 35 wound thereon adjacent the head of the filling carrier, as indicated in Fig. 3, and such bunch predetermines the amount of waste that may be on the filling carrier when it is ejected.

The main winds 36 are placed upon the filling carrier, as usual, and as indicated in Fig. 2, the main winds 36 are formed cone-shaped, as at 37, from a short distance tipward of the bunch toward and partially covering the bunch, and the feeler, presently to be described, is formed to cooperate with the main filling winds along an element of the cone adjacent the head of the filling carrier.

The rear end portion of the feeler carrier 19 is provided with a slot or opening 38, Fig. 1, and at one side of the feeler carrier

19 the feeler 39 is pivotally mounted upon a stud 40, the dimensions of the feeler being such that should it be moved on its pivotal support 40 from the position indicated in Fig. 2 to that indicated in Fig. 3, the feeler 70 will pass into the slot or opening and be housed or covered by the overlying portions of the rear end of the feeler carrier.

The feeler 39 is provided with a series of teeth 41 and such series of teeth are alined in substantial parallelism with the element of the cone winds 37, with the result that each of the teeth of the series will contact with the conical winds and hold the feeler from movement longitudinally of the shuttle relative to the feeler carrier so long as a working supply of filling is present in the shuttle on a detecting beat.

The rear end portion 42 of the feeler carrier 19 may be bifurcated, as indicated in the drawings, to form the slot or opening for the reception of the feeler, and such construction constitutes a good practical form of the present invention.

In order to hold the feeler in its normal feeling position, as indicated in Fig. 2, a light spring extends transversely of the feeler carrier and engages the forwardly extending tail portion 43 of the feeler. A stop 43* constituted by the side of the feeler carrier limits the action of the spring. In the present instance of the invention, the feeler carrier is provided with a retaining notch 44 and similarly the forwardly extending tail 43 of the feeler is provided with a retaining notch 45 into each of which an end portion 46 of a light spring 47 is placed, the action of the spring being transversely of the feeler carrier 19 and acting to hold the feeler in the position indicated in Fig. 2 with permissive movement, however, in a direction longitudinally of the shuttle under the forward pressure when filling is substantially exhausted on a detecting beat.

Under normal weaving conditions with a working supply of filling in the shuttle, the series of alined teeth 41 of the feeler engage the element of the conical winds 37, such element being indicated by the line *a*.

Adjacent the trailing end of the alined feeler teeth, the feeler is provided with a rearwardly extending projection or smooth hump 48, the purpose of which is to engage the surface of the filling carrier when filling is substantially exhausted and after the feeler itself has been initially moved in a direction longitudinally of the shuttle, the result being that the projection or hump 48 will give an increased swinging movement to the feeler on its pivotal support and not only withdraw the feeler teeth forwardly from the surface of the filling carrier, but cause them to be housed within the slot or opening 38 within the rear end portion of the feeler carrier. This extra forward move-

ment of the teeth of the feeler prevents the teeth of the feeler itself from engagement with the bunch 35, with the result that the bunch 35 which is predeterminedly supplied with the desired amount of filling, will remain intact upon the filling carrier when replenishment is effected.

Inasmuch as the present invention has for one of its purposes the action of the feeler near the head of the filling carrier on the conical winds adjacent the head, the rear end portion of the feeler carrier at 49 is cut away or made inclined corresponding to the incline joining the head and barrel of the filling carrier, as indicated in Fig. 3.

When a working supply of filling is present in the shuttle on a detecting beat, the alined teeth of the feeler will engage an element of the conical wind and serve to hold the feeler from movement longitudinally of the shuttle on frontward movement of the lay, and also cause the feeler carrier to be moved frontwardly and thus prevent the bunter 24 from engagement with the shuttle or other surface on the lay, so that the actuator 22 will remain in its inoperative position. When, however, the filling has become substantially exhausted on a detecting beat, the frontward pressure of the surface of the filling carrier against the alined teeth 41 of the feeler will initially turn the feeler on its pivotal connection with the feeler carrier until, when the projection or hump 48, at the trailing end of the alined teeth, engages the barrel of the filling carrier, the feeler will be further turned upon its pivotal support to carry the alined teeth away from the filling carrier and into the slot or opening 38 in the rear end of the feeler carrier, without danger of such teeth coming in contact with the bunch 35 adjacent the head of the bobbin. When the condition last described has been effected, the bunter 24 will engage the shuttle or other surface on the lay, as indicated in Fig. 4, and thereby turn the actuator 22 into operative relation with the transmitter arm 15, and, on frontward movement of the feeler carrier, filling replenishment will be effected.

What is claimed is:

1. In a feeler mechanism for filling replenishing looms, the combination of a feeler carrier mounted for movement towards and from the front of the loom, an actuator supported by the carrier in position to engage a part carried by the lay when the filling is substantially exhausted and arranged to be operated by said engagement to effect replenishment of filling, a feeler pivotally mounted on the feeler carrier to cooperate with a filling carrier having a bunch adjacent the head thereof and conical winds tipward of the bunch and having teeth arranged in alined series corresponding with the inclina-

tion of the element of the conical winds adjacent to the head of the filling carrier, a spring normally acting to maintain the feeler in said relation to the conical winds and yieldable on frontward pressure of the denuded filling carrier to permit the feeler to slip towards the filling bunch when the main filling winds on the carrier are substantially exhausted.

2. In a feeler mechanism for filling replenishing looms, the combination of a feeler carrier mounted for movement towards and from the front of the loom, an actuator mounted on the carrier to engage a surface on the lay when the filling is substantially exhausted to effect replenishment of filling, a feeler pivotally mounted on the feeler carrier to cooperate with a filling carrier having a bunch adjacent the head thereof and conical winds tipward of the bunch and having teeth arranged in alined series to correspond to an element of the conical winds adjacent the head of the filling carrier, a spring and feeler stop acting normally to hold the feeler in feeling position with the series of teeth alined for engagement with the conical surface of filling adjacent the head of the filling carrier and permitting movement of the feeler towards the head of the filling carrier by the frontward pressure when the main winds of filling are substantially exhausted.

3. In a feeler mechanism for looms, the combination of a feeler carrier mounted for movement towards and from the front of the loom, a feeler pivotally mounted on the feeler carrier to cooperate with a filling carrier having a bunch adjacent the head thereof and conical winds tipward of the bunch, a series of teeth on the feeler alined in series to correspond to an element of the conical winds and adapted to be displaced towards the bunch by the frontward pressure of the filling carrier when the conical winds have been substantially exhausted and prior to depletion of the bunch, an actuator mounted on the feeler carrier for engagement with a surface on the lay when the feeler is displaced towards the bunch by the frontward pressure, and means operated by the actuator for effecting replenishment of filling.

4. In a feeler mechanism for looms, the combination of a feeler carrier mounted for movement towards and from the front of the loom having a horizontal recess at its rearward end, a feeler pivotally mounted on the feeler carrier to cooperate with a filling carrier having a bunch adjacent the head thereof and conical winds tipward of the bunch, a series of teeth on the feeler alined in series to correspond to an element of the conical winds and adapted to be displaced towards the bunch by the frontward pressure of the filling carrier when the conical winds have

- been substantially exhausted and prior to depletion of the bunch and enter said recess in the rear end of the feeler carrier, an actuator mounted on the feeler carrier for engagement with a surface on the lay when the feeler is displaced towards the bunch by the frontward pressure, and means operated by the actuator for effecting replenishment of filling.
5. In a feeler mechanism for looms, the combination of a feeler carrier mounted for movement towards and from the front of the loom, an actuator mounted on the feeler carrier adapted to engage a surface on the lay when the filling is substantially exhausted, a feeler mounted on the feeler carrier for displacement longitudinally of the shuttle by the frontward pressure upon the feeler when filling is substantially exhausted and having a series of teeth, and a projection on the feeler which is moved into engagement with the filling carrier or bobbin within the shuttle when the feeler is displaced longitudinally of the filling carrier by frontward pressure upon the feeler and causes the feeler to be further displaced to thereby remove the feeler teeth from engagement with the filling carrier.
6. In a feeler mechanism for looms, the combination of a feeler carrier mounted for movement towards and from the front of the loom, a feeler having teeth and pivotally mounted on the feeler carrier and held from movement longitudinally of the shuttle by the filling until substantially exhaustion thereof, and a feeler displacer formed as a smooth projection adjacent the trailing end of the series of feeler teeth to engage the filling carrier or bobbin within the shuttle when the filling is substantially exhausted on a detecting beat and the feeler has been initially moved longitudinally of the shuttle by frontward pressure upon the feeler to withdraw the teeth from contact with the filling carrier within the shuttle.

In testimony whereof, I have signed my name to this specification.

THOMAS H. McGOWAN, Sr.
